Inventor
Ray G. Dawson

By Clarence O'Brien
Attorney

UNITED STATES PATENT OFFICE.

RAY G. DAWSON, OF SALEM, OREGON.

WRENCH.

Application filed April 21, 1927. Serial No. 185,597.

This invention relates to new and useful improvements in wrenches of the inner sliding jaw type and aims to provide a highly novel, simple and easily operable means whereby the sliding jaw may be readily adjusted with respect to the stationary jaw and wherein said sliding jaw may be rigidly secured in adjusted position.

In the drawing wherein like reference characters indicate corresponding parts throughout both of the views.

Figure 1 is a view mainly in side elevation disclosing my improved wrench, the sliding jaw locking unit being partially disclosed in cross section, and

Figure 2 is a transverse section taken substantially upon the line 2—2 of Figure 1 for more clearly disclosing the locking means for said sliding jaw.

Now having particular reference to the drawing, my novel wrench consists of an elongated handle shank 5 having a stationary jaw 6 upon one end thereof. Slidable upon the shank 5 is a movable jaw 7 formed at its inner sides with a longitudinal shank 8 the end of which is formed with a lateral sleeve 9 through which the shank 5 of the wrench is engageable. The inner face of the sliding jaw shank 8 is in spaced relation with the adjacent surface of the handle shank 5 and is formed with spaced teeth 10. Directly adjacent the outward sliding limit of movement of the movable jaw 7 the edge of the handle shank 5 adjacent the sliding jaw shank 8 is formed with a longitudinal notch 11 within which is transversely slidably mounted a plate 12 having teeth 13 complementary to the teeth 10 of the sliding jaw shank 8. The opposite longitudinal edges of this plate 12 are formed with skirts 14—14 for engagement upon the opposite faces of the stationary jaw shank 5. Said jaw shank 5 within the confines of the notch 11 is formed with a transverse threaded opening 15 through which is threaded a screw 16, the outer end of which is threaded

as at 17, while the inner end thereof bears against the inner wall of the locking plate 12 so that after the sliding jaw 7 has been moved toward or away from the stationary jaw 6 to a predetermined point, an inward turning of this screw 16 will bind the teeth of the plate 12 within the teeth 10 of the sliding shank 7 to prevent any further movement of the sliding jaw.

It will thus be seen that I have provided a highly novel, simple, and inexpensive form of sliding jaw wrench wherein means is provided for facilitating the easy and rapid adjustment of the sliding jaw and the positive securing of the same in adjusted position.

Having thus described the invention, what I claim is:—

In a wrench of the character described, a handle shank, said shank being provided with a jaw at its outer end, a jaw slidable on said shank, a split sleeve slidable on said shank, a bar connecting said slidable jaw and sleeve rigidly together and in spaced parallel relation to the shank, said bar being formed at its inner edge with teeth, the shank being formed with a notch, and U-shaped pawl having the outer surface of its bight portion ribbed, for cooperation with the bar teeth, said pawl being adapted for arrangement with its bight portion seated in said notch of the shank, the leg portion thereof engaging the opposite sides of the shank so as to engage with the portions of the jaw and of the sleeve sliding on said sides of the shank, respectively to limit the motion of the jaw in both directions, and a threaded element adapted to be threaded transversely through the shank so that its inner end will project into the notch of the shank for engagement with said pawl for forcing the same into mesh with the teeth of the bar.

In testimony whereof I affix my signature.

RAY G. DAWSON.
